ATTORNEY

UNITED STATES PATENT OFFICE.

LOVELL R. VAN TASSEL, OF REYNOLDSVILLE, PENNSYLVANIA.

SHOEING APPARATUS.

Application filed March 24, 1922. Serial No. 546,474.

To all whom it may concern:

Be it known that I, LOVELL R. VAN TASSEL, a citizen of the United States, residing at Reynoldsville, in the county of Jefferson 5 and State of Pennsylvania, have invented new and useful Improvements in Shoeing Apparatus, of which the following is a specification.

This invention relates to a device for the 10 use of blacksmiths in shoeing horses, and the object is to provide particular means for supporting the foot of the animal, permitting greater freedom of movement of the smith and relieving him of unnecessary 15 work incident to the common practice of holding the foot while applying the shoe.

A further object is to provide an apparatus which shall include means for restricting the movement of the horse, and foot 20 supporting devices or posts, adjustable with reference to the height and slideable on floor rails, so that the exact position required may be secured.

A still further object is to provide particular means for supporting and counterbalancing the rails or devices designed to restrict the movements of the horse.

With the foregoing and other objects in view, the invention consists in the novel 30 construction and arrangement of elements described and claimed, it being understood that modifications may be made within the scope of the claims, without departing from the spirit of the invention.

In the drawings, Figure 1 shows the apparatus in side elevation; Figure 2 is a top plan view; Figure 3 is an end elevation; Figure 4 shows a foot support in vertical section and elevation; Figure 5 is a transverse section through the telescoping elements of the foot support; Figure 6 is a detail view of the upper member of the foot support.

In practice the apparatus will usually be 45 constructed for the accommodation of two horses, but in the present instance it is only necessary to describe one complete unit including two side rails, the supporting means therefore, two floor rails and the sliding foot support or posts associated therewith.

The floor rails are suitably spaced apart 55 and are in parallel relation, it being the intention that the horse shall stand between the floor rails, and the side rails for con-

fining the movements of the animal are mounted above the floor rails and are parallel therewith.

The floor rails 10 and 12 are connected by 60 braces 11 and are spaced slightly from the surface of the floor, in order to provide for the movement of the sliding foot posts. This post includes a base 13 and a pair of guiding elements 14 and 15 of approximately U-shape, the central portion of each of said 65 elements extending across the upper side of the base, and the free ends being inwardly turned and deflected under the floor rails. Mounted on the base is a post 15', and extending through the base in position to contact with the upper surface of rails 10 or 12 as the case may be, are threaded elements or 70 screws 16 and 17 controlled by devices 18 readily grasped by the hand.

The movable element of the post includes 75 a tubular member 20 which telescopes over the stationary element of the post, this tubular member being provided with a clamping element including a collar having projecting ears 22 and 23, between which is 80 mounted a cam lever or the like 23', the operative end of which projects through slot 24 and engages the stationary member of the post.

Carried by the upper end of the tubular 85 member is a block 26 having an inclined portion 27, the surface of which is channeled in the manner shown, in order that the foot of the animal may rest on this block and be in proper position to permit the 90 smith to affix the shoe. The block may be carried by a plate 38 supported by a stirrup or the like secured to the tubular member by means of bolts or rivets.

It will be observed therefore that the foot 95 support is adjustable vertically and is slideable lengthwise of the floor rails, and may be secured by the stirrups specified.

The side rails 35, 36 are mounted to permit of vertical movement, so that they may 100 be raised or lowered according to circumstances, the rails being preferably formed of iron pipes and supported and counterbalanced as indicated below.

At the rear portion of the apparatus 105 stanchions 37, 38 are mounted, their upper and lower ends being threaded into plates, such as 39, secured to the floor and ceiling.

Mounted on each stanchion is a vertically 110 adjustable clamp including a hook, the

clamp being designated 39' and the hook 40. Extending between oppositely located hooks is a chain 42 designed to support the rear ends of the side rails 35, 36, the ends 5 of these rails engaging certain of the links of the chain. Also connected with each side rail, at the rear end thereof, is a rope 43 passing over a pulley 44 or 45 as the case may be, the free or opposite end of the rope 10 being secured at 45'.

Above the forward portion of the apparatus, at each side, is a pulley 46 (one being shown), and over these pulleys the ropes 48, 49 are passed, the ends of the ropes having 15 connection with weights 50, 51, acting as counterbalances. Clamps 55, 56 render the forward ends of bars 35 and 36 rigid or 20 slideable with reference to inclined bars 53, 54.

20 What is claimed is:

1. In a device of the class described, a pair of rails to be supported in parallel relation above the floor of a building, a foot

support mounted beneath one of the rails, means for supporting and counterbalancing 25 corresponding ends of the rails, stanchions mounted in spaced relation at points adjacent the opposite ends of the rails, and a flexible device connecting the stanchions and 30 adapted to support the adjacent ends of the rails.

2. In a device of the class described, a pair of rails to be supported in parallel relation, bars for connecting corresponding 35 ends of the rails with a ceiling, counterbalance means connected with the same ends of the rails, stanchions near the opposite ends of the rails, a flexible device adjustably connected with the stanchions and connected with the rails, and means for raising and 40 lowering the flexible device and changing the elevation of the rail ends connected therewith.

In testimony whereof I affix my signature.

LOVELL R. VAN TASSEL.
